UNITED STATES PATENT OFFICE.

JOSEPH EDGAR MICHAEL, OF KINGSPORT, TENNESSEE.

SANITARY CUSPIDOR.

1,232,951.

Specification of Letters Patent. Patented July 10, 1917.

Application filed November 17, 1916. Serial No. 131,909.

To all whom it may concern:

Be it known that I, JOSEPH E. MICHAEL, a citizen of the United States, residing at Kingsport, in the county of Sullivan and State of Tennessee, have invented a new and useful Sanitary Cuspidor, of which the following is a specification.

The device forming the subject matter of this application is a spittoon, and one object 10 of the invention is to provide novel means for holding in place within the spittoon, a destructible bag or lining which may be removed and thrown away, thereby rendering it unnecessary to wash the spittoon.

Another object of the invention is to provide a spittoon having a destructible lining, 15 the upper portion of which is made of fire-proof material, so that the lining cannot be ignited by matches, lighted butts and the like, cast into the spittoon, the bottom portion of the bag or lining being of water-proof material.

It is within the province of the disclosure to improve generally and to enhance the 20 utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within 25 the scope of what is claimed, without departing from the spirit of the invention.

In the drawings:—

Figure 1 shows in elevation, a spittoon constructed in accordance with the present 30 invention;

Fig. 2 is a vertical section taken through the spittoon delineated in Fig. 1;

Fig. 3 is a cross section on the line 3—3 of Fig. 2;

Fig. 4 is a fragmental vertical section showing a modified form of the invention.

In carrying out the present invention there is provided, as shown in Figs. 1 and 2, a cup-like base 1 on which is superposed 40 a tubular neck 2. The neck 2 may be of any desired form, but in the present instance it is shown as of hour-glass shape, being broadened slightly at its lower end, to cooperate with the cup-like base 1. The neck 2 may be interengaged with the base 1 in any desired manner. In the present in-

stance, the base 1 is provided upon its upper end with an upstanding continuous flange 3 received within a depending continuous flange 4 on the lower end of the neck 2. 60 Superposed on the upper edge of the neck 2 is a ring 5. The ring 5 may be interengaged with the upper end of the neck 2 in any way which is considered expedient. In the present instance, but not of necessity, 65 the ring 5 has a continuous rib 6 fitting into a continuous groove 7 formed in the upper edge of the neck 2.

Disposed within the contour of the spittoon constructed as above described, is a bag 70 or lining including a cup-shaped bottom 8 and a top part 8^a. The bottom 8 and the top 8^a preferably are formed in one piece. The bottom part 8 is made out of some water-proof substance, such as paraffin 75 paper, and the top part 8^a of the lining is rendered fire-proof, in any suitable way. The parts 8 and 8^a are made in one piece, or are secured together. The bottom part 8 of the lining fits closely within the contour of the base 1, and the upper edge of the top part 8^a of the lining is bound between the ring 5 and the upper end of the neck 2, the top part 8^a of the lining being compressed into the groove 7 by the rib 6, 80 so that the lining will be held securely in place. Owing to the fact that the upper edge of the lining is engaged beneath the ring 5, it will be impossible for material to run down between the lining 8 and the inner 85 wall of the neck 2. The spittoon, therefore, will at all times be in a cleanly condition.

When it is desired to remove the bag 8, the ring 5 is lifted off the neck 2 and the neck 2 is lifted off of the base 1. The lining 95 8—8^a may then be pulled out of the base and be thrown away.

In assembling the structure, the bottom part 8 of the lining is placed in the base 1 and is contracted slightly, whereupon the 100 neck 2 is slid over the lining. The lining is then shaped to the interior of the neck 2 and is pressed laterally to engage the upper edge of the neck, whereupon the ring 5 is mounted in place to cover and hold the 105 upper edge of the lining.

Owing to the fact that the upper part 8 of the lining is made out of fire-proof material, the lining cannot be ignited by matches, butts and the like which are thrown 110 into the spittoon. However, since the bottom part 8 of the lining is made out of

water-proof material, the spittoon will be in a clean condition when the lining and its contents are drawn out of the spittoon.

In Fig. 4 of the drawings, a slight modification in the invention is shown. The neck of the spittoon appears at 27 and the base of the spittoon is shown at 25, these parts being interengaged at 26, as before. The base portion of the lining, which is 10 water proof, appears at 28, and the top portion of the lining, which is fire-proof, is shown at 29. In this form of the invention, the bottom part 28 of the lining and the top part 29 thereof are made in separate 15 pieces, and are overlapped as shown at 30. Saving as hereinbefore specifically modified, the device of Fig. 4 is constructed like the structure shown in Fig. 2.

Having thus described the invention, what 20 is claimed is:—

1. A spittoon comprising a cup-like base; a neck mounted on the base and flared toward its upper and lower ends to define a reduced intermediate passage; and a de- 25 structible bag-like lining in the base and

extended upwardly through the reduced intermediate passage and shaped to conform to the neck, the neck being removably mounted on the base, to permit the lining to be shaped to the base before the lining is inserted into the reduced passage and shaped thereto.

2. In a device of the class described, a spittoon; a destructible lining in the spittoon and having its upper end extended outwardly across the upper edge of the spittoon; and a ring resting on the lining and supported by the upper edge of the spittoon, the upper edge of the spittoon and the lower edge of the ring being provided with circum- 30 scribing interlocked tongued and grooved 35 elements coöperating with the upper end of the lining to put a crimp therein.

In testimony that I claim the foregoing as my own, I have hereto affixed my signature in the presence of two witnesses.

JOSEPH EDGAR MICHAEL.
